US00D842982S

(12) **United States Design Patent** (10) Patent No.: **US D842,982 S**
(45) Date of Patent: ** *Mar. 12, 2019

(54) **HARDHAT SUSPENSION ADAPTER FOR HALF FACEPIECE RESPIRATORS**

(71) Applicant: **3M INNOVATIVE PROPERTIES COMPANY**, St. Paul, MN (US)

(72) Inventor: **David M. Castiglione**, Hudson, WI (US)

(73) Assignee: **3M Innovative Properties Company**, St. Paul, MN (US)

(*) Notice: This patent is subject to a terminal disclaimer.

(**) Term: **15 Years**

(21) Appl. No.: **29/577,725**

(22) Filed: **Sep. 15, 2016**

(56)

(57) CLAIM

The ornamental design for a hardhat suspension adapter for half facepiece respirators, as shown and described.

DESCRIPTION

FIG. 1 is a front perspective view showing a new design for a hardhat suspension adapter for half facepiece respirators;

FIG. 2 is a front view thereof;

FIG. 3 is a side view thereof;

FIG. 4 is a back view thereof;

FIG. 5 is a second side view thereof;

FIG. 6 is a top view thereof; and,

FIG. 7 is a bottom view thereof.

The portions of the hardhat suspension adapter for half facepiece respirators in FIGS. 1 to 7 shown in broken lines are included to show features that form no part of the claimed design.
